F. A. RUNDLE,
SAFETY LIMIT SWITCH,
APPLICATION FILED DEC. 27, 1915.

1,236,485.

Patented Aug. 14, 1917.

UNITED STATES PATENT OFFICE.

FRED A. RUNDLE, OF HARVEY, ILLINOIS.

SAFETY-LIMIT SWITCH.

1,236,485.

Specification of Letters Patent. Patented Aug. 14, 1917.

Application filed December 27, 1915. Serial No. 68,834.

To all whom it may concern:

Be it known that I, FRED A. RUNDLE, a citizen of the United States, residing at Harvey, in the county of Cook and State of Illinois, have invented a certain new and useful Improvement in Safety-Limit Switches, of which the following is a specification.

This invention is a safety limit switch applicable in general to machines of all kinds, 10 but especially to hoisting mechanisms such as traveling cranes for cutting off the electric current when the mechanism has reached the safety limit in its path of travel in a given direction.

15 The object of the invention is to provide a device of this kind which can be operated by the moving mechanism without said moving mechanism coming to a too abrupt stop and one which automatically closes itself whenever the moving mechanism of the machine 20 reverses its direction of motion and recedes from the danger position at which it opened the switch.

25 The invention consists in a device which is capable of carrying out these objects, which can be easily and cheaply made and installed, which is satisfactory in operation and in one having the special features and details of construction hereafter more fully 30 set forth.

In the drawings,

Figure 1 is a side,

Fig. 2 an end, and

Fig. 3 a plan view of mechanism illustrating this invention in its preferred form.

The particular embodiment of the machine here illustrated is applied to a lifting mechanism such as a traveling crane having a main frame 10. Rigidly attached 40 to this frame 10 by any suitable means, such as the bolts 12, is a bracket 14, preferably overhanging the frame as shown, so that a depending lug bearing 16 integral with it may clear the frame, as clearly appears in Fig. 1. Slidable through this bearing is a rod or shaft 18 provided with an elongated slot 20 in which limit screw 22 located in the bearing 16 enters to permit longitudinal movement of the rod 18 up and 45 down between full line and dotted line position of Fig. 1 without it being possible to remove the rod 18 in either direction from the bearing 16 except, of course, by removing the bolt 22. On the lower end of rod 18 50 is a plate 24 adapted to be engaged by the pulleys 26 journaled in block 28 at 30. To

this block 28 is attached the usual load lifting hook (not shown). Over the pulleys 26 passes the lifting rope or chain 29 whose middle traverses equalizing pulley 31 mounted on frame 10 in the ordinary manner. Power devices, not here shown, manipulating rope 28 in the ordinary manner elevate pulleys 26 and block 28. Similarly, in the ordinary manner, the weight attached to block 28 moves it downward whenever the motor controlling it is reversed.

When the power lifting mechanism has raised the block 28 to the position of Fig. 1, the pulleys 26 strike the lower end of shaft 18 and plate 24 and any further movement of the pulleys 26 upward moves shaft 18 upward until it finally reaches the dotted line position of Fig. 1. When the block 28 and pulleys 26 begin to move downward, the weight of rod or shaft 18 carries it downward from the dotted line position until it finally reaches the full line position of Fig. 1. In other words, the rod or shaft 18 is movable upward by the load during a certain period in the path of travel of the load and it returns to normal position whenever the load is not in that portion of its path of travel.

Suitably located at one side of the central axis of the rod or shaft 18 and on the bracket 14 is a horizontal pivot or shaft 32 carrying a movable lever 34 adapted to swing in a vertical plane which includes the axis of shaft 18 and to normally lie in a position across the end of said shaft as clearly appears in Figs. 1 and 3. In fact, a lug or stop 36 is provided so that it cannot move entirely out of the path of travel of rod or shaft 18, as fully appears in the dotted line position of Fig. 1. This lever 34 is, as clearly appears in Fig. 3, made with an aperture 38 lying in the plane of the rod or shaft 18 of such a size and shape that, as clearly appears in dotted lines of Fig. 1, the rod 18 may pass through and beyond lever 34, leaving said lever leaning against the rod, the result being that as rod 18 is moved downward, gravity will move lever 34 downward as soon as the upper end of rod 18 clears the notch 38. In the particular form of mechanism here illustrated, the aperture 38, as clearly appears in Figs. 2 and 3, takes the form of an opening between the bifurcated ends 34^a and 34^b of the lever 34. The bifurcation of the lever is such as to permit rod 18 to be straddled by lever 34 interme-

- diate of its length. In the particular case here illustrated, each of these arms is provided with an insulated switch contact member 40 to which are respectively connected electric wires 42 and 44, but only one of these arms and one of these switch contacts need be provided if the device is to be used as a single pole switch instead of the double pole switch here illustrated.
- 10 The electric switch contacts 40 engage suitable opposite contacts 46 mounted upon suitable supports 48 on bracket 14 and the latter are, of course, provided with suitable electric wires 50.
- 15 In the operation of the device, assume that the parts are in the position of full lines in Fig. 1 with the switch 40—46 closed, and that the load carrying block 28 is moving upward from the full line position toward
- 20 the dotted line position. As the distance from pivot 32 to the center line of rod 18 is less than the distance from said pivot to the switch contacts 40—46 it will be seen that it only takes a very slight movement of the rod 18 upward to elevate lever 34 sufficiently to separate contacts 40 from contacts 46, thus cutting off the current which propels the motor which is raising the block 28. If the momentum of the load in
- 25 moving upward is sufficient to carry the block 28 beyond the point which thus opens the switch, block 28 and consequently the load is free to move upward until rod 18 reaches the dotted line position of Fig. 1.
- 30 But in all positions after the switch has been opened, the lever 34 continues to bear against the rod 18 and is ready to, under the action of gravity, return to normal position, thus insuring the supplying of power
- 35 to the power operating mechanism just as soon as the load recedes from the danger position which caused the switch to open. It will thus be seen that the switch device opens
- 40 quickly and sharply as soon as the limit of safe movement of the load has been reached and that it automatically closes as soon as the load recedes from the danger position.
- 45 By providing the notch or recess 38 in lever 34 it is possible to place the rod 18 close to pivot 32 of lever 34 thus securing a quick action of the switch, as heretofore described, and yet have the lever 34 always lean against the rod 18 at a sufficient angle
- 50 so that gravity has a powerful influence on the lever 34 to close the switch in the manner described.
- 55 Spring 60 is provided for two purposes; to check the final movement of rod 18 and load following it as it reaches its upper position, thus avoiding injury to the trolley, and to start the rod downward against any possible friction as soon as the load begins to move downward.
- 60 Having thus described my invention, what

I claim as new, and desire to secure by Letters Patent, is:—

1. In a device of the class described, an apertured operating lever and a reciprocatable member movable toward and from said lever so located that in a portion of its path of travel it engages said lever to move it and during the remainder of its path of travel passes through the aperture in said lever but does not operate said lever. 75
2. In a device of the class described, an apertured operating lever so located that it is movable in one direction by gravity, and a member reciprocatable toward said lever to first move it a given distance contrary to gravity and then pass through the aperture in the lever leaving the lever supported by said reciprocatable member, for the purposes set forth. 80
3. In mechanism of the class described, 85 the combination with two opposite switch points to be connected and disconnected, an apertured lever member carrying at one end one of said switch points and pivoted at its other end, and a reciprocatable member operable by the machine controlled by the switch engaging said lever so that as said member is reciprocated in one direction it first moves said lever to open said switch and then passes through the aperture in the 90 lever, for the purposes set forth.
4. In a device of the class described, the combination with a suitable frame carrying a switch point, a member movably attached to the frame and carrying a second switch 100 contact engageable with the first one, and a second movable member reciprocatable with reference to the frame but in a different direction from the direction of movement of the first mentioned movable member adapted 105 to, in moving, engage said first mentioned movable member for a sufficient length of time to separate said switch contact and thereafter, in its movement, move through an aperture in said first mentioned movable 110 member, for the purposes set forth.
5. In a device of the class described, a bifurcated operating lever so located that it is movable in one direction by gravity, and a member reciprocatable toward said member 115 to first move it in a given direction contrary to gravity and then pass between the bifurcated parts in the lever leaving the lever straddling the reciprocatable member, for the purposes set forth. 120
6. In a device of the class described, in combination with a suitable frame carrying a switch point, a member movably attached to the frame carrying a switch contact engageable with the switch point on the frame, 125 a second member reciprocatable with reference to the frame but in a different direction from the direction of movement of the first mentioned movable member adapted to, in moving, engage said first mentioned member 130

for a sufficient length of time to operate said switch contacts and thereafter in its movement move through the bifurcation in the first mentioned movable member, for the 5 purposes set forth.

7. A device of the class described, in combination with a fixed support and a pair of switch points, an operating lever pivoted to the support, bifurcated at its free end, 10 switch points upon the respective bifurcated end parts of the lever engageable in one position with the switch points upon the fixed support, a reciprocatable member movable through the fixed support toward and from 15 said lever so located that in a portion of its

path of travel it engages said lever to move it to separate the switch points, and during the remainder of its path of travel passes between the bifurcated ends of the lever, said ends being so proportioned that in this 20 position the lever straddles the movable lever.

In witness whereof, I have hereunto subscribed my name in the presence of two witnesses.

FRED A. RUNDLE.
